UNITED STATES PATENT OFFICE.

DAVID W. YORK, OF NORTH ABINGTON, MASSACHUSETTS, ASSIGNOR OF ONE-TENTH TO
BERTHA B. YORK AND ONE-TENTH TO E. L. CHAPMAN, BOTH OF NORTH ABINGTON,
MASSACHUSETTS.

STEAM-DISSIPATING ATTACHMENT FOR COOK-STOVES AND RANGES.

1,189,030.

Specification of Letters Patent.

Patented June 27, 1916.

Application filed March 10, 1916. Serial No. 83,385.

To all whom it may concern:

Be it known that I, DAVID W. YORK, a citizen of the United States, residing at North Abington, in the county of Plymouth 5 and State of Massachusetts, have invented new and useful Improvements in Steam-Dissipating Attachments for Cook-Stoves and Ranges, of which the following is a specification.

10 This invention relates to a dissipating attachment for cook stoves and ranges, and its object is to provide an attachment whereby the steam generated within the cooking vessels upon the stoves may be collected and 15 discharged directly into the smoke pipe leading to the flue, thus preventing the steam from escaping into the kitchen or room in which the stove is arranged.

20 A further object of the invention is to provide a device of the character described which may be applied to any ordinary cook stove or range, for use in conjunction with one or more vessels at a time, and which includes special covers for application to the 25 cooking vessels by means of which the escape of steam from the vessels will be freely permitted and the steam gathered for conduction to the smoke pipe.

The invention consists of the features of 30 construction, combination and arrangement of parts hereinafter fully described and claimed, reference being had to the accompanying drawing in which:—

Figure 1 is a top plan view of a stove or 35 range showing the application of the invention, parts appearing in section. Fig. 2 is a front elevation of the same. Fig. 3 is a detail view of the steam conductor removed. Fig. 4 is a transverse sectional view through 40 the same, and showing one of the connectors. Fig. 5 is a detail view of a vessel cover.

Referring to the drawings, 1 designates a cook stove or range of any of the constructions in general use, and 2 a smoke pipe 45 connected with the smoke outlet thereof, and which is adapted for attachment to a main pipe or flue 3 leading to the chimney, whereby the smoke and products of combustion from the stove are discharged to the 50 atmosphere.

My improved steam eliminator comprises a steam collecting pipe 4 disposed horizontally above the top 5 of the stove and preferably extending in a direction from front

to rear thereof. This collecting pipe 4 is 55 connected with a discharge pipe 6 by means of a U-shaped intermediate pipe or union 7 which connects the rear end of the pipe 4 with the outer end of the pipe 6. The pipe 6 extends parallel with the arms of the 60 union 7 in rear of the back shelf support 8 of the stove, and the arms of the union 7 lie on opposite sides of this shelf support and are connected by the return bend there- 65 of or adjacent one end of said support, the inner end of the pipe 6 being fitted over a tube 9 upon the smoke outlet pipe 2, by means of which the discharge pipe 6 and, through which, the collecting pipe 4, are 70 in communication with said outlet pipe and the flue through which the products of combustion are discharged. It will accordingly be understood that the passage of the smoke and products of combustion through the 75 pipe 2 causes a draft or partial suction in the pipes 4, 6 and 7, whereby any steam contained in said pipes will be drawn into the flue and discharged.

The pipe 4 is closed at its forward end, as indicated at 10, and said pipe is provided 80 with a desired number or series of inlet tubes 11 for the admission of the steam from the cooking vessels upon the stove, U-shaped connectors 12 being provided for uniting said tubes with the respective ves- 85 sels to be placed in communication with the collecting pipe. For this purpose, a cover 13 of ordinary construction but which is provided with a discharge tube 14 is fur- 90 nished for closing each vessel, and in connecting such vessel with the pipe 4 a connecting member 12 is used, one arm of which is attached to a tube 11 of the pipe 4 and the other arm of which is connected with the tube 14 of the cover of the vessel which is 95 to be coupled to the eliminating pipe. Thus it will be understood that one or more ves- 100 sels may be simultaneously connected with the pipe, and that the connectors may be of suitable size for connection with vessels dis- posed at different points, enabling any de- sired number to be connected with the elim- inator at will, dependent upon the number of inlet tubes 11 provided.

In the operation of the device, it will of 105 course be apparent that as the steam is generated by the vessels, it will pass through the suction produced in the pipe 4 first into

said pipe and then through the pipes 7 and 6 to the pipe 2 and thence to the chimney, all of the steam being thus prevented from escaping into the room and discharged into the chimney in an obvious manner, the advantages and conveniences of which will be manifest. Preferably a supporting member or leg 15 is provided upon the pipe 4 to brace and sustain the same from the top of 10 the stove.

I claim:—

In a device of a class described, in combination, a stove, a chimney mounted at one side of said stove, a bracket mounted upon 15 said stove at the opposite side thereof with respect to said chimney, an elongated steam-collection pipe secured at one end upon

said bracket and extending substantially throughout the width of the stove and having a U-shaped connection with the chimney so as to be supported above the stove, a longitudinal series of projections forming inlet nipples upon said steam collection pipe, and a plurality of interchangeable receiving curved pipes secured upon said nipples at 20 one end and adapted to extend downwardly with their opposite ends for connection with steam-supplying tubes.

In testimony whereof I affix my signature in presence of two witnesses.

DAVID W. YORK.
